UNITED STATES PATENT OFFICE.

MELLVIN E. ERICKSON AND ARTHUR W. MOGREN, OF GRANTSBURG, WISCONSIN.

SACK-HOLDER.

1,145,297.

Specification of Letters Patent. Patented July 6, 1915.

Application filed December 1, 1913. Serial No. 894,138.

To all whom it may concern:

Be it known that we, MELLVIN E. ERICKSON and ARTHUR W. MOGREN, citizens of the United States, residing at Grantsburg, in the county of Burnett and State of Wisconsin, have invented certain new and useful Improvements in Sack-Holders, of which the following is a specification.

Our invention relates to sack holders, the primary object of our invention being the provision of a sack holder upon which the sack may be readily mounted when it is to be filled and from which the sack may be removed when filled without any material effort, no lifting of the sack and contents being necessary.

A further object of our invention is to provide a sack holder which may be adjusted for use with various sizes of sacks, including sacks of different lengths as well as sacks of different widths.

A still further object of our invention is to construct a sack holder so arranged that the sack is yieldably held with its mouth open and elevated in such a manner that the sack either rests at its lower end upon a support or is held slightly above the support.

A still further object of our invention is to provide a sack holder which shall be simple and economical in construction and at the same time efficient and durable in operation.

With these and other objects in view, our invention will be more fully described, illustrated in the accompanying drawings, and then specifically pointed out in the claims which are attached to and form a part of this application.

In the drawings:—Figure 1 is a perspective view of our improved sack holder, showing the same in operation; Fig. 2 is a top plan view of the sack holder, showing the sack supporting arms in active position in full lines, a sack being shown in place by dotted lines and the inactive position of the sack holding arms being also shown in dotted lines; Fig. 3 is an end view of the sack holder; Fig. 4 is a fragmentary sectional view taken on the line 4—4 of Fig. 3 and illustrating the manner in which the sack holding arms are mounted in the frame; Fig. 5 is a sectional view on the line 5—5 of Fig. 3, showing the means provided for vertical adjustment of the sack holder; Fig. 6 is a

perspective view of one of the sack engaging hooks.

Corresponding and like parts are referred to in the following description and indicated in all the views of the drawings by the same reference characters.

The preferred embodiment of our invention consists primarily of a supporting base or platform 10, frame 11 and sack holding arms 12, the frame extending vertically from the base and the sack holding arms being swingingly mounted at the upper end of the frame.

More specifically the base, which is preferably rectangular in shape, is usually constructed from a plurality of boards 13 secured together at their ends by cleats 14 nailed or otherwise fastened to the lower faces of the boards and serving not only as a means for securing the boards together, but also as supporting feet to hold the platform in slightly raised position above the floor. The frame 11 includes a pair of vertical spaced apart telescopic standards, each of which is formed of two main members 15 and 16, both of these members being tubular in construction. Metallic piping is usually employed for this frame and the lowermost of these members, that is the member 15, is threaded at its lower end to engage in the threaded socket 17 secured to one of the corners of the platform. The upper end of this member 15 is externally threaded to receive the internally threaded tapered coupling 18.

A rod 19 extends at its ends into the upper end of the member 15 and the lower end of the member 16, being adjustably secured with respect to the member 15 by a wing bolt 20 threaded through the coupling and engaging the rod and in the member 16 by a set nut 21. Each of the members 16 is provided at its upper end with a T-coupling 22 and a transversely extending brace 23 is threaded by its ends into the horizontally extending sockets of these T-couplings. As will be seen by reference to Fig. 1, the above described frame extends vertically from the rear part of the platform 10 and the upper portion thereof may be readily adjusted at various heights by proper manipulation of the wing bolt 20 and set nut 21.

The sack supporting arms 12 are swingingly mounted in the upper ends of the frame members 16, each including a body portion 24 which extends within the member

16 and an angularly extended portion 25 terminating in a downwardly and outwardly directed sack engaging hook 26.

In order to hold the sack supporting arms 5 with their free ends away from each other so that they will stretch open the mouth of the sack which they support, we provide each of them with a helical spring 28 which, in each instance, surrounds the body portion 24 of the arm having one end passed into a bore 29 formed therein and the opposite end 30 extended into the cross brace 23 of the frame, the tendency of these springs being to swing the free ends of the arms 10 outwardly and rearwardly with respect to the sack holder.

In constructing the sack holder, the frame members 15 are mounted upon the platform, the connecting rods 19 adjustably secured 20 therein and the frame members 16, carrying the T-couplings 27, adjustably mounted upon the upper ends of the rods 19. The body portions of the swinging arms 12 are then extended into the frame members 16 25 until the openings 29 are in alinement with the horizontal socket of the couplings. Lengths of stiff resilient wire are then inserted through such sockets to seat at their ends in the bores 29 of the arms 12 when 30 the arms are rotated several times to wind the resilient wire about the body portions thereof to form the springs 28. The free ends of the spring forming wires are then inserted in the ends of the cross brace 23 35 of the frame and said brace applied. In addition to these swinging sack supporting arms, the cross brace 23 is provided adjacent each end with a sack engaging hook 31. Each of these hooks includes a shank 32 40 which is passed through the transversely disposed horizontal bore 33 in the cross brace 23 and threaded at its free end to receive a nut 34. The bill portions of these 45 hooks extend at substantially right angles to the shank portions and are spaced slightly in front of the brace 23, as best shown in Fig. 2 of the drawings, the hooks being blunt to prevent tearing of the sack. The cross brace is preferably provided with 50 a plurality of spaced squared bores or openings 33 in order that the hooks may be changed from one to the other to adjust the sack holder for use with sacks of varying widths. The squared shanks of the hooks 55 hold them against turning.

In employing our improved sack holder, the edge of the sack is first engaged by the hooks 31 in the manner shown in Fig. 1. The swinging arms 12 are then moved inwardly and the sack positioned upon the hooked terminals 26 thereof, in the manner shown in Fig. 1, the sack being put on the hooks from the bottom. The arms are then released and, due to the action of the springs 28, swung away from each other to spread

the mouth of the sack, this spreading of the sack preventing the same from slipping from the hooks of the cross brace. As soon as the sack has been filled, the arms are swung inwardly to permit disengagement of 70 the sack from the hooked terminals, such disengagement being readily accomplished as the bill portions of the hooks extend horizontally. As soon as the sack is released from the swinging arms, it may be readily 75 freed from the hooks 31. It is therefore clear that the sack may not only be readily applied to the sack holder, but that the sack, when filled, may be removed without the necessity of lifting the sack and its contents. 80

The mounting of the arm holding springs 28 in the tubular standards and cross brace of the supporting frame, as set forth, results in a number of important advantages. The springs, when thus mounted, are housed and 85 therefore protected and any danger of the sack supported upon the sack holder becoming caught upon the springs prevented. Furthermore, the construction and arrangement described is much simpler than other 90 possible arrangements, such as mounting the springs exteriorly of the standards and projecting one end of each spring through slots formed in the standards to engage the arms. Furthermore, with the arrangement disclosed, the springs serve to hold the arms 95 against accidental displacement from the standards, no other securing means for the arms being required.

Although we have illustrated and de- 100 scribed our sack holder in all its details, it will of course be understood that we do not wish to limit ourselves to the specific details of construction, as various minor changes, within the scope of the appended claims, 105 may be made at any time, without in the slightest degree departing from the spirit of our invention.

Having thus described the invention, what is claimed as new is:

1. A sack holder including supporting members, a cross brace connecting free ends of the members, sack supporting arms swingingly mounted in such ends of the members, and springs mounted in the members and 110 cross brace and secured to the sack engaging arms to normally hold the same with their free ends away from each other.

2. A sack-holder including tubular supporting standards, T-couplings upon the 120 ends of the standards, a transverse brace connecting the T-couplings, sack supporting arms swingingly mounted in the upper ends of the standards, those portions of the arms within the standards being provided with 125 transverse bores, and helical springs surrounding those portions of the arms within the standards, one end of each spring extending through the bore of the adjacent arm and the opposite end of each spring ex- 130

tending into the adjacent end of the cross brace.

3. A sack holder including tubular supports, a tubular brace connecting the supports, sack supporting arms swingingly mounted in the upper ends of the supports, and helical springs surrounding the arms within the supports, one end of each spring being secured to the adjacent arm and the

other end extended into the adjacent end of 10 the brace.

In testimony whereof we affix our signatures in presence of two witnesses.
